United States Patent Office

Des. 211,162
Patented May 28, 1968

211,162

SPIRAL STAIRCASE

Helge Ragner Albrektsen, 1554 Eastern Ave.,
Covington, Ky. 41018

Filed Apr. 15, 1966, Ser. No. 1,902

Term of patent 14 years

(Cl. D13—7)

FIG. 2.

FIG. 3.

FIGURE 1, is a perspective view of the stairway of this invention;

FIGURE 2 is a plan view of the stairway of this invention as seen from the top floor;

FIGURE 3 is a perspective view showing the top portion thereof.

The dominant features of my design reside in the portions shown in full lines.

I claim:

The ornamental design for a spiral staircase as shown and described.
